(57) **CLAIM**

The ornamental design for a license plate frame featuring dollar signs and diamonds, as shown and described.

DESCRIPTION

FIG. 1 is a front, top, right side perspective view of a license plate frame featuring dollar signs and diamonds showing my new design;

FIG. 2 is a front elevation view thereof;

FIG. 3 is a rear elevation view thereof;

FIG. 4 is a left side elevation view thereof, the right side elevation view being the same;

FIG. 5 is a top plan view thereof; and,

FIG. 6 is a bottom plan view thereof.

The broken line showing of the tabs and mounting holes is for illustrative purposes only and forms no part of the claimed design.
